INDEXING MECHANISM

George John Engert, Manitowoc, Wis.

Application January 8, 1943, Serial No. 471,721

3 Claims. (Cl. 90—56)

My invention relates to improvements in index mechanism for use in setting work into different positions preparatory to machine operations thereon.

The principal object of my invention is to provide simply constructed, easily installed mechanism whereby such work as shafts, for instance, may be quickly and accurately set into different angular and other positions in a milling machine, or the like, for the cutting of keyways in different locations thereon.

Other and subordinate objects are also comprehended by my invention, all of which, together with the precise nature of my improvements, will be readily understood when the succeeding description and claims are read with reference to the drawings accompanying and forming part of the specification.

In said drawings:

Figure 1 is a view in side elevation of my improved indexing mechanism in its preferred embodiment.

Figure 2 is a view in transverse section taken on the line 2—2 of Figure 1.

Figure 3 is a view in plan.

Figure 4 is a view in end elevation.

Figure 5 is a view in longitudinal vertical section taken on the line 5—5 of Figure 1, and

Figure 6 is a view in vertical transverse section taken on the line 6—6 of Figure 1.

Referring to the drawings by numerals, the basic elements of my improved indexing mechanism are a pair of substantially rectangular work supports 1, 2 adapted to be opposed in laterally spaced relation on the table 3 of a milling machine, not shown, and upon opposite sides of the milling cutter, not shown, with broad sides facing. Each support, 1, 2 embodies a skeleton half section 4 on one side of the vertical transverse center, for reducing weight, and a solid half section 5, with the exceptions presently noted, on the other side of said center. A pair of slotted bottom lugs 6 extend from opposite sides of the solid half section 5, by means of which, and bolts 7 extending into one of the usual, longitudinal key grooves 8 in the table 3, said supports may be anchored to said table 3 and adjusted into different set positions along the same. A similar pair of slotted lugs 9 extending from the sides of the rear half section 4 of each support, 1, 2, provide for anchoring said supports to a machine table.

A pair of longitudinally split bushings 10 are provided in bores 10' in the upper portions of the half sections 5 in axial alignment for clamp-

ingly engaging a shaft 11 and are anchored in said bores 10' as by screws 10''. A pair of substantially cylindrical clamping members 12 are slidably mounted in each half section 5 below the bushing 10 in a transverse bore 13 for adjustment in axial alignment toward each other to engage curved notches 14 therein with the bushing 10 to flex the latter into clamping engagement with the shaft 11. The members 12 of each pair are adjustable by means of a screw bolt 15 extended through axial bores 15' in said members with one end threaded, as at 16 into the bore of one member and its other end having a collar 17 thereon bearing against one end of the other member and equipped with a hand lever 18 secured thereto, as at 19. A pair of key forming screw bolts 20 turned into one side of each support 1, 2 and into keyways 21 in the members 12, shown by dotted lines in Figure 6, 20 prevents the members 12 from rotating in the bore 13. The members 12 of each pair are urged apart by a coil spring 20' interposed between the pair and surrounding the screw bolt 15, as shown in Figure 6, and for pushing the pair apart 25 to prevent the same from interfering with insertion of bushings 10.

An indexing disk 22 having a longitudinally split clamping hub 23 is provided for clamping on one end of the shaft 11 against the outer face 30 of the adjacent supports 1, 2, said hub having a pair of lugs 24 upon each side thereof arranged for drawing together in pairs by thumb screws 25 to clamp the hub 23 to the shaft 11. The indexing disk 22 is provided on one face thereof with a circular edge scale 26 graduated in degrees of a circle and numbered appropriately at every ten degrees from opposite sides of a zero graduation 27 to 180 degree graduation 28.

The scale 26 is designed to be read against a vernier scale 29 at the top of said disk provided on a plate 30 formed on an arm 31 having an angular elongated base 32 adapted to fit in a flat bottomed socket 33, one of which is provided in the top of each support, 1, 2, to extend lengthwise across the same in vertical alignment with the axis of the bore 10'. A thumb screw 34 extends through the base 32 for turning into a bore 35, one of which is provided in the bottom of each socket 33.

A flat annular level carrying member 36 is fitted in a circular seat 37 provided in the graduated base of the indexing disk 22, said member being rotatable in the disk concentrically about the shaft 11 for adjustment into different set positions in said disk to correspondingly adjust

a spirit level 38 disposed thereon endwise circumferentially of said disk. Thumb screws 39 are provided in the disk 22 for turning against said member 36 to lock the member in adjusted position.

When it is desired to mill or cut a number of keyways, as at 40, 41, in the shaft 11 remote from the ends thereof and in longitudinally spaced and angular relation, the shaft 11 is clamped adjacent its ends in the holders 1, 2 in the manner already described. The index disk 22 is then placed on one end of the shaft 11 against one support, set into zero position against the vernier scale 29 and clamped to the shaft, also as previously described. The member 36 is then set in the disk 22 until the spirit level 38 indicates level and is then clamped to the disk 22. The first keyway 40 is then cut. To cut the second keyway 41, for example, in 30 degree-30' angular relation to the first keyway 40, the shaft 11 is released in the supports 1, 2, the index disk 22, together with the shaft 11, is rotated in the proper direction to 30 degree-30' reading against the vernier scale 29, the member 36 reset until the spirit level 38 again indicates level at this setting, the disk 22 and shaft 11 pulled in the proper direction a distance according to the longitudinal spacing required. The level is then checked, and the shaft 11 clamped in the supports 1, 2. The second keyway 41 is then cut. This procedure is followed for cutting any number of keyways in the shaft.

By attaching the arm 31 in the socket 32 of either support, 1 or 2, and placing the indexing disk 22 on the adjacent end of the shaft 11, an operator may work from either side of the machine, or in other words, from either end of the shaft 11.

The spirit level 38 is utilized as will be understood from the foregoing to prevent loss of degrees or minutes in extending the shaft 11, or, in other words, in adjusting the shaft longitudinally.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. Indexing apparatus for use on the table of a milling machine or the like to set a shaft in different longitudinal and angular positions relative to the milling tool comprising a pair of supports for opposite ends of the shaft adapted to be fixed to said table and embodying split tu-

bular clamps for the extension of said ends of the shaft therethrough and for flexing against said shaft to clampingly engage the same, manipulative means on each support for flexing said sleeves, a graduated indexing disk for attachment to the shaft, a pointer on one support for cooperation with the graduations on said disk, a spirit level, and means to mount said level on said disk for adjustment circumferentially of the same into different set positions, the last-mentioned means comprising an annular level carrying member rotatable in said disk concentrically thereof.

2. Indexing apparatus for use on the table of a milling machine or the like to set a shaft in different longitudinal and angular positions relative to the milling tool comprising a pair of supports for opposite ends of the shaft adapted to be fixed to said table and embodying split tubular clamps for the extension of said ends of the shaft therethrough and for flexing against said shaft to clampingly engage the same, manipulative means on each support for flexing said sleeves, a graduated indexing disk for attachment to the shaft, a pointer on one support for cooperation with the graduations on said disk, a spirit level, and means to mount said level on said disk for adjustment circumferentially of the same into different set positions, the last-mentioned means comprising an annular level carrying member rotatable in said disk concentrically thereof, and devices for clamping the member to said disk.

3. Indexing apparatus for use on the table of a milling machine or the like, or for layout or inspection purposes, to set a shaft in different longitudinal and angular positions relative to the milling tool, layout or inspection requirements, comprising a pair of supports for opposite ends of the shaft adapted to be fixed to a machine or layout table and embodying split tubular clamps in pairs of varying inside diameters to suit work, for the extension of said ends of shaft therethrough and for flexing against said shaft to clampingly engage the same, manipulative means on each support for flexing said sleeves, a graduated indexing disk for attachment to the shaft, a vernier setting scale on one support for cooperation with the graduations on said disk, a spirit level and means to mount said level on said disk for adjustment circumferentially of the same into different set positions, the last mentioned means comprising an annular level carrying member rotatable in said disk concentrically thereof, and devices for clamping the member to said disk.

GEORGE JOHN ENGERT.
